UNITED STATES PATENT OFFICE.

THOMAS E. ADAMS, OF BEATRICE, NEBRASKA.

SLIP JOINT FOR WELL CASINGS.

Application filed February 1, 1927. Serial No. 165,164.

My invention relates to slip joints for well casings and similar tubular sections, its object being the provision of joint members at the opposite ends of the casing sections of such construction that the sections may be quickly and easily interfitted without leaving any exposed rough edges on the inner side of the casing, the construction including also an easily operated latching device for effectively preventing the accidental disassembling of the sections after they have been united. Furthermore, it is my object to so design the joint members that they may be formed at a low labor and material cost and so as to utilize waste material which is found in all shops in which sheet metal is worked, the labor cost being cut down by means of construction design permitting the employment of spot welding for uniting the various parts and of power driven swages for performing the forming operations.

Having in view these objects and others which will be pointed out in the following description, I will now refer to the drawings, in which:

Figure 1 is a view in perspective showing the interlocking joint portions of two sections of well casing.

Figure 2 is a sectional view taken lengthwise through the interlocking portions of two joint sections.

Figure 3 is a view in perspective of a casing joint of slightly modified form.

Figure 4 is a view in lengthwise section through one wall of the joint members shown in Figure 3.

Since the joint was initially and primarily designed for the interlocking of sections of well casing, the invention will be described with particular reference to this use. Such casing is generally made from galvanized sheet steel which is formed into cylindrical sections and provided with end portions which are interfitting. When the cylindrical sections are made of sheet metal of the lighter gauges, the double lock roll seam is employed, as shown at the top portion of Figure 1. In metal of the heavier gauges such a joint would be apt to loosen the zinc coat and the seam must therefore be formed in some other manner, as for example, by riveting or welding. The novel features of my joint are applicable to all sheet metal casings regardless of the form of the seam.

In carrying out my invention I provide each section of the casing with a male and female end. In the case of the male end, only an outwardly turned annular ridge 12 is formed to define the inner limit of that end portion. Surrounding the section 10 on its male end and adjacent the annular ridge 12 is a ring 13 which is preferably spot welded to the section and which is provided with openings between the ring and the body of the section for the latching device which will subsequently be described.

The opposite end portion of the section is also provided with an annular groove 14 which in this case is inwardly directed. The portion from the groove 14 to the outer end of the section is enlarged in diameter to twice the thickness of the metal by swaging, so that in lengthwise section the walls 75 are in the form of an ogee curve. It will be apparent from an inspection of Figure 2 that when two sections are joined together in end to end relation, their inner walls will be continuous except for the annular groove at 12 and for the annular ridge at 14. Both of these, however, are smooth curves and the ridge at 14 completely covers the cut end of the male portion of the section so that no rough edges can be exposed. The walls of the male end are aligned with the walls of the body portions of its section and of the companion section.

The joint is further provided with external means for locking the sections together so as to prevent any accidental displacement or the breaking of the joint. As before explained, the ring 13 surrounds the male end of the section 10. A similar ring 15 of somewhat larger diameter surrounds the female end of the section 11 and this also is provided with openings for the latching devices. The ring 15 is secured to the section by spot welding. The latching device itself consists of tapering strips 16 of sheet metal. These strips 16 are secured in place at the time the ring 15 is secured to the section 11 and they also are spot welded so that the section and the ring 15 and the latching devices 16 are in effect integral. The projecting ends of the tapering latching members 16 are turned at 17 over the outer surface of the ring 15. The positions of the latching members 16 and the positions of the gaps between the ring 13 and the section 10 are such that they will register when the sections 10 and 11 are joined. They may be uniformly spaced

about the circumference of the sections, or if preferred, they may be so spaced that the sections will not interlock except in one definite axial position. In some instances 5 this may be desirable in order to prevent the seams of the sections from being placed too near each other when the sections are joined by clumsy or inexperienced workmen.

In assembling the casing it is only necessary to force the sections together in end to end relation in such a manner that the tongues of the latching devices 16 will enter the gaps between the ring 13 and the section 10 and by then turning over the projection 15 ends of the latching devices against the outer surface of the ring 13.

The double lock roll seam which unites the two edges to form a section in tubular form is generally of considerable thickness. The 20 inside of the section is smooth and the extra thickness is all on the outside, thus making tight interlocking of the sections difficult. This may be avoided by swaging the female end of the section throughout its length so 25 as to provide a longitudinal groove on its inner surface, this groove having a width and depth sufficient to accommodate the roll on the outer surface of the male section. By properly locating this groove in its relation 30 to the tongues 16 and the gaps in the ring 13 it serves as a guide for properly assembling the sections.

It is obvious, of course, that the invention 35 is susceptible of numerous variations, the number of these variations being so great that it is impossible to illustrate all of them. One of these modified forms is shown in Figures 3 and 4. In the construction the male end of the section is provided with a 40 tongue 16' by slitting the metal and turning the tongue outwardly so that it lies on the outer side of the female end of the section as shown in Figure 4. The lock is produced by slitting the metal of the female end of 45 the section transversely to form a loop 13' which is spaced from the body of the metal. In assembling the two sections the tongue 16'

will pass through the loop 13' so that it may be turned down on the loop. The same result could be produced by using scraps of 50 sheet metal and welding them to the sections to provide either a tongue 16' or a loop 13' or both.

Having thus described my invention in such full, clear, and exact terms that its construction and operation will be readily understood by others skilled in the art to which it pertains, what I claim as new and desire to secure by Letters Patent of the United States is:

1. In combination, a pair of tubular sections having interfitting male and female end portions, an annular ridge on the outer surface of said male portion and an annular ridge on the inner surface of said female portion, bands surrounding and secured to said male and female end portions respectively, said ridges and said bands being adapted to prevent the telescoping of said sections, and straps secured to the band on 55 said female portions and releasably secured to the band on said male portion.

2. In combination, a pair of cylindrical sections having interfitting male and female end portions, the male portion of the section 75 having the diameter of the body portion of the section and being separated therefrom by an annular outwardly projecting ridge, the female portion of the other of said two sections having a diameter greater than the 80 diameter of the body portion of the section and being separated therefrom by an annular inwardly projecting ridge, rings surrounding said male and female end portions respectively and secured thereto, said two 85 rings constituting stops to prevent the telescoping of said sections, and straps positioned between said rings and said male and female end portions of said sections, said straps being fixedly secured to said female 90 portion and releasably secured to said ring surrounding said male portion.

In testimony whereof I affix my signature.
THOMAS E. ADAMS.
